CLAIM

We claim the ornamental design for a bus shelter, as shown.

DESCRIPTION

FIG. 1—a front view of the bus shelter;

FIG. 2—a rear view;

FIG. 3—a right side view;

FIG. 4—a left side view;

FIG. 5—a top view;

FIG. 6—a bottom view;

FIG. 7—a perspective view; and,

FIG. 8—a second perspective view.

The broken lines in FIG. 6 depict portions of the bus shelter that form no part of the claimed design.
